UNITED STATES PATENT OFFICE.

SIDNEY O. BIGNEY, OF ATTLEBORO, MASSACHUSETTS.

to holding a belt in adjusted position about the body of the wearer.

Serial No. 391,262. Filed June 24, 1930.

1,360,360. Patented Nov. 30, 1920.

Specification of Letters Patent. Application filed June 24, 1930. Serial No. 391,262.

To all whom it may concern:

Be it known that I, SIDNEY O. BIGNEY, a citizen of the United States, residing at Attleboro, in the county of Bristol and State 5 of Massachusetts, have invented certain new and useful Improvements in Belt-Buckles, of which the following is a specification.

This invention relates to belt buckles of the class adapted to bind a belt in adjusted 10 position about the body of the wearer; and the invention has for its object to provide a buckle of the clamp lever type in which the lever is provided with a roller for binding the belt against the inner face of the body 15 of the buckle with a rolling grip, to prevent abrading or injuring the belt upon being so engaged, and it is also found that such a clamp with a rolling grip, may be much more easily moved to engaging position, 20 than a clamp having a rigid biting edge.

The nature and advantages of the invention will be better understood when the following detail description is taken in connection with the accompanying drawings, the 25 invention residing in the combination and arrangement of parts as claimed.

In the drawings forming part of this specification, like numerals of reference indicate similar parts in the several views and 30 wherein:

Figure 1 is a sectional side elevation of my improved roller grip buckle as applied to a belt.

Fig. 2 is a perspective view showing the 35 under side of the clamp lever with the gripping clamp mounted thereon.

Fig. 3 is a plan view of the under side of the clamp lever.

Fig. 4 is a central transverse section 40 through the lever and its clamp roll.

Fig. 5 is a perspective view showing the under side of my improved buckle.

It is found in practice that the usual rigid 45 lip which is formed on the ordinary lever grip buckle, has a tendency to scrape, abrade and injure the surface of the belt engaged by it, which effect is entirely eliminated by the use of my roller lever grip.

The following is a detailed description of 50 one construction by which this rolling lever grip on a belt may be accomplished:

With reference to the drawings, 10 designates the body of the buckle which is usually formed of precious or plated metal, and is 55 provided with two side walls 11 turned back at substantially right angles to the plane of

the front plate 12. Each of these side walls is hereinafter shown as being provided with ears 13 pierced at 14 for the reception of pivot pins or lugs 15 formed on the side 60 edges of the clamp lever 16.

This clamp lever is preferably formed of sheet stock and has a portion 17 removed therefrom leaving a bar 18, thereby forming a bail through which the end 19 of the belt 65 may be passed and secured.

On the under side of this clamp lever I have provided a pair of ears 20 in which I have rotatably mounted a roll 21, the surface of which roll is preferably corrugated. 70

This roll may be pivoted in these ears 20 by the insertion of pins or by any other suitable pivoting means.

In connecting the belt to this buckle it is only necessary to attach the end 19 to the 75 belt while the other end 22 is passed beneath the inwardly-turned flanges 23 and also beneath the clamp lever, which at this time is tipped up at an angle, as illustrated by dotted lines in Fig. 1, to permit the ready positioning of this end of the belt thereunder. Then by exerting a tension on the portion 19 of the belt in the direction of its normal line of pull the clamp lever swings down into the position shown in full lines, which 80 swinging action causes the roller 21 to engage the other portion 22 of the belt and roll to its gripping position to so firmly bind the belt against the inner face of the body portion that it is impossible for it to slip 85 from any adjusted position and this without in any way scraping, cutting or injuring the surface of the belt.

It is also to be noted that by providing a roller for the gripping bar instead of a fixed 90 sharp rigid lip, the lever is swung down into operative position with the minimum amount of effort, as the gripping roller simply revolves or rolls against the face of the belt in swinging to the binding position. 100

Then again when it is desired to release the belt the minimum amount of effort is required to swing the roller lever out of its gripping contact with the belt.

The device is extremely simple in construction and effective in its operation.

The foregoing description is directed solely toward the construction illustrated, but I desire it to be understood that I reserve the privilege of resorting to all the 111 mechanical changes to which the device is susceptible, the invention being defined and

limited only by the terms of the appended claims.

I claim:

1. A belt buckle comprising a body, a clamp lever pivotally mounted in said body and a roller carried by said lever for engaging and binding the belt against the body with a rolling grip.

2. A belt buckle comprising a body, a clamp lever pivotally mounted in said body and to which one end of the belt is adapted to be secured, a roller clamp carried by said lever to engage the other end of said belt

with a rolling grip to bind the same against the inner face of said body portion.

15

3. A belt buckle comprising a body having rearwardly turned side walls, a clamp lever pivotally mounted in said walls a portion of said lever forming a bail for receiving one end of the belt, pivot ears on the under side 20 of said lever, and a roller clamp mounted in said ears to engage the other portion of the belt with a rolling grip to bind the same against the inner face of the body portion.

25 In testimony whereof I affix my signature.

SIDNEY O. BIGNEY.
